UNITED STATES PATENT OFFICE.

HENRY J. HEINZ, OF PITTSBURG, PENNSYLVANIA.

DESIGN FOR A SPOON.

SPECIFICATION forming part of Design No. 21,895, dated October 11, 1892.

Application filed September 8, 1892. Serial No 445,371. Term of patent 7 years.

To all whom it may concern:

Be it known that I, HENRY J. HEINZ, of Pittsburgh, in the county of Allegheny and State of Pennsylvania, have invented a new and original Design for Spoons, of which the following is a full, clear, and exact description, reference being had to the accompanying drawings, forming part of this specification, in which—

Figure 1 shows in plan view a spoon embodying my design, and Fig. 2 shows the same in side view.

Like symbols of reference indicate like parts in each.

The design consists in a spoon shaped sub-

stantially as shown in the drawings and as herein described.

In the drawings, 2 represents a straight handle, terminating in a longitudinally-curved and transversely-straight paddle-shaped widened blade 4.

I claim—

The design for a spoon, substantially as herein shown and described.

In testimony whereof I have hereunto set my hand this 5th day of September, A. D. 1892.

HENRY J. HEINZ.
